(57) **CLAIM**

The ornamental design for a body shape for keyboard, as shown and described.

DESCRIPTION

FIG. 1 is a perspective view of a body shape for keyboard showing our new design;

FIG. 2 is a top view thereof;

FIG. 3 is a rear view thereof;

FIG. 4 is a front view thereof;

FIG. 5 is a left side view thereof; and,

FIG. 6 is a right side view thereof.

The broken line showings of the keys are for illustrative purposes only and form no part of the claimed design.
